UNITED STATES PATENT OFFICE

JACOB KRONHEIM, OF CLEVELAND, OHIO

CHAIR AND COUCH

Application filed April 6, 1931. Serial No. 528,023.

My invention relates to an improvement in resilient bottoms for upholstered furnitures such as chairs and couches, and more particularly to connecting devices and means for attaching and supporting a yielding bottom within a chair or couch frame preliminary to upholstering the same. In general the object of my improvement is to provide looped attachment means which may readily be sleeved through openings in the wooden frame or rails and automatically interlocked with the outer face of the rail by attaching the yielding bottom to the looped portions thereof in a stretched state. For such purpose the attaching means according to the invention are made of elastic material, preferably steel wire and shaped to permit a yielding action between their main looped body portion to which the yielding bottom is attached and their holding or retaining extensions, all as hereinafter more fully described and particularly pointed out in the accompanying drawing in which Fig. 1 is a sectional view of a chair or couch frame showing the attachment means embodying my invention. Fig. 2 is an enlarged sectional view horizontally through one corner of the structure of Fig. 1, Fig. 3 a perspective view of an attachment device according to the invention, and Fig. 4 a similar view of a modified form thereof.

Referring now to the drawing, the open rectangular frame A made of wooden rails 2 supports yieldingly a resilient seat or bottom 4 generally comprising a flexible sheet B of textile fabric, upon which a series of helical springs S are seated. Bottom 4 is stretched under tension between side rails 2 and a front rail 2' and for such purpose a plurality of yielding connections are provided, which include a series of short helical springs C and S-shaped hooked members E which are attached to the marginal wire reinforcement members 10 of bottom 4 and hooked to the rounded looped ends 5 of steel wire attaching devices or members D. Each member D is formed with straight substantially parallel legs or main body portions 6 dimensioned to extend slightly at opposite sides of rails 2-2' so that the looped ends 5

thereof may readily be connected to the helical springs C or S-shaped hooks E, thus connecting the rails 2-2' with bottom 4. These hooks E are preferably employed for connecting the front edge of the bottom to the front rail 2' in order to impart a degree of rigidity to this part of the bottom. The main body portions 6 of the member D are closely related to each other to permit insertion of these portions through relatively small openings 7 in rails 2-2' through which openings body portions 6 are inserted from the outside of frame A, so that oppositely bent branches 8 thereof may engage the outside face of the rail and interlock therewith. 55 These branch portions 8 extend at an acute angle relatively to main body portions 6 preferably of approximately 75°, and the outer ends thereof are cut on a bias to form sharp pointed prongs 9 with their points facing toward the outer face of rails 2-2' against which they are seated. 60 65 70

In practice, when attaching devices D are placed as described and connected under tension with the bottom 4 through the medium of springs C or S-shaped hooked members E, prongs 9 penetrate slightly and interlock with rails 2-2' and thereby create pivot points for branch portions 8. Any increase or decrease of tension on attaching devices D induces pivotal movement of branch portions 8 around their pivot points, and also a longitudinal movement of main body portions 6 of attaching devices D, such movement being resisted by the inherent tension 75 80 85 of said attaching devices. At the same time lateral movement of main body portions 6 takes place. This lateral movement of the body portions 6 is in an approaching direction relatively to each other under increasing tension on attaching devices D thereby eliminating or decreasing frictional contact between these body portions and the wall of the openings 7 through which these portions extend. When tension is relieved the portions 6 will of course have a tendency to move 90 95 away from each other.

The attaching devices D are generally secured to the rails in a horizontal plane but where conditions require that they lie in 100

another plane in order to adapt the looped ends to the helical springs C or S-shaped hooks E the body portions 6 may be bent accordingly.

5 As stated above portions 6 under variations in tension on these connecting looped end portions will be induced to shift laterally of each other and thereby decrease or increase the size of the looped ends 5. Too 10 great decrease in the size of such loops may create a binding action between said loops and the hook ends of springs C or S-shaped hooks E. To avoid such action I show in Fig. 15 4 a modified form of an attaching device D' in which the body portions are twisted near the outer ends thereof at 9 to effect increase in the size of loop 5, with consequent increased tension on device D'.

20 The connecting devices described enable the building and installation of a yielding bottom in chairs or couches rapidly and permit use of shorter springs with larger flexible sheets of textile fabric without decreasing the spring action and flexibility of the 25 yielding base by reason of the fact that the yielding members D extend through the rails. The arrangement permits use of smaller and cheaper springs and also provides a slight spring action at the front rail.

30 What I claim, is:

1. A chair or couch frame having, or being provided with, a series of openings in the rails of said frame, a yielding bottom supported within said frame, and a series of looped attaching devices extending through said openings and connecting said bottom with said frame; each of said attaching devices including a looped main body extending through one of said openings into the 40 inside of said frame and resilient branches inclined at an acute angle to said main body, the free ends of said inclined branches engaging the outside face of said frame for resilient connection of said bottom and frame.

45 2. A chair or couch frame having, or being provided with, a series of openings in the rails of said frame, a yielding bottom supported and stretched within said frame, and 50 a series of resilient and looped attaching devices connecting said bottom with said frame, each of said attaching devices including a looped main body extending through one of said openings into the inside of said frame and resilient branches inclined at an acute angle to the main body of said device and seated with their outer ends upon the outside face of said frame for resiliently connecting said bottom and frame.

55 60 3. A chair or couch frame having, or being provided with, a series of openings in the rails of said frame, a yielding bottom supported within said frame, and looped attaching devices connecting said bottom with said frame, said devices engaging the out-

side face of said rails and extending with their looped portions through said openings into the inside of said frame, and each of said attaching devices including a looped main body portion having closely related straight legs and oppositely arranged pointed branches inclined at an acute angle to said legs and seated with their pointed ends upon the outside face of said rails to permit longitudinal shifting of said looped main body within its opening.

70 75 4. An attaching device for resiliently connecting a yielding bottom to a chair or couch frame, comprising a steel wire bent to form a main body portion having closely related straight legs and a loop portion, and oppositely directed branch portions arranged at an acute angle to said legs.

80 85 5. A chair or couch frame having, or being provided with a series of openings in the rails of said frame, a yielding bottom supported and stretched within said frame, resilient attaching devices seated against the outside face of said rails in alignment with said openings, and short helical springs connecting said yielding bottom with said resilient attaching devices, each of said attaching devices including a main body portion axially aligned with one of said openings and oppositely directed branches inclined at an 90 acute angle to said main body portion and engaging with their free ends the outside face of said frame to permit axial shifting of said main body portion under varying 95 stresses.

100 In testimony whereof I affix my signature.
JACOB KRONHEIM.
